United States Patent

Des. 242,208

Patented Nov. 9, 1976

242,208

POWER UNIT FOR A BLENDER OR THE LIKE

Alfred W. Madl, Glendale, and Charles J. Kirschling, Milwaukee, Wis., assignors to Oster Corporation, Milwaukee, Wis.

Filed Nov. 12, 1973, Ser. No. 414,971

Term of patent 14 years

Int. Cl. D7—04

U.S. Cl. D7—154

Published under the Second Trial Voluntary Protest Program on Feb. 10, 1976, as document No. B414,971

FIG. 1 is a perspective view of a power unit for a blender or the like embodying our new design;

FIG. 2 is a front elevational view thereof;

FIG. 3 is a side elevational view thereof;

FIG. 4 is a top plan view thereof; and

FIG. 5 is a rear elevational view thereof.

The bottom is substantially unornamented.

We claim:

The ornamental design for a power unit for a blender or the like, as shown and described.
